US00D958369S

(12) **United States Design Patent** (10) **Patent No.:** **US D958,369 S**
(45) **Date of Patent:** **** Jul. 19, 2022**

(54) **PREMAXILLA VOMER PLATE**

(71) Applicant: **Carsten Matuschek**, Falkensee (DE)

(72) Inventor: **Carsten Matuschek**, Falkensee (DE)

(**) Term: **15 Years**

(21) Appl. No.: **35/511,037**

(22) Filed: **Jun. 19, 2020**

(80) **Hague Agreement Data**

Int. Filing Date: **Jun. 19, 2020**

Int. Reg. No.: **DM/210607**

Int. Reg. Date: **Jun. 19, 2020**

Int. Reg. Pub. Date: **Dec. 25, 2020**

(30) **Foreign Application Priority Data**

Dec. 19, 2019 (EM) 007433776

(51) **LOC (13) Cl.** **24-03**

(52) **U.S. Cl.**

USPC **D24/155**

(58) **Field of Classification Search**

USPC D24/155, 176, 196, 152, 180

CPC A61C 7/287; A61C 7/10

See application file for complete search history.
